UNITED STATES PATENT OFFICE.

ALBERT HARRISON DE VOE, OF WESTFIELD, NEW JERSEY, ASSIGNOR TO THE SINGER MANUFACTURING COMPANY, OF ELIZABETH, NEW JERSEY, A CORPORATION OF NEW JERSEY.

HEMMER.

Application filed September 20, 1924. Serial No. 738,746.

This invention relates to sewing machine hemmers and has for an object to provide a hemmer which will evenly and uniformly hem a margin of fabric having an irregular or jagged edge, or offset edge-portions such as are commonly present at the beginning or end of a previously formed cross-seam. A further object of the invention is to provide a hemmer into which a fabric edge may be quickly and easily inserted and which will freely receive and turn the edge of the work to be hemmed regardless of cross-seams, serrations, off-sets or other irregularities at the edge of the work.

According to the present improvement the body of the hemmer is made from a piece of sheet-metal bent into the form of a scroll or diminishing spiral. The inner enclosed edge-portion of the scroll is free from the adjacent or main wall portions thereof and its bottom portion is cut away at the delivery end of the hemmer. Preferably, the inner portion of the hemmer scroll is in the form of a hollow or concavo-convex forming tongue or arbor disposed forwardly of the exit from the hem-forming passageway; the free edge of the arbor being in the form of a longitudinally progressing spiral terminating at the delivery end of the hemmer and of a sense opposite to that of the spirally formed hemmer body. In other words, if the hemmer is in the form of a counter-clockwise diminishing spiral terminating in an inner enclosed and free edge, such edge is in the form of a longitudinally and clockwise progressing spiral terminating at the delivery end of the hemmer. The hemmer includes a work-supporting portion or platform which, together with the hemmer body, has a front edge extending spirally rearwardly toward the delivery end of the hemmer as far as the arbor where it merges into the front edge of the latter and continues spirally in a reverse direction, or forwardly, to the front end of the arbor.

By virtue of the foregoing constructive features, the passageway at the delivery end of the hemmer is clear of restrictions to the free and easy egress of the hemmed edge-portion of work, even though the latter varies in bulk due to irregularities such as above described. The spiral front edge of the hemmer and the concavo-convex arbor operate to smoothly turn and fold in any irregularities in the edge of the fabric. To

enable the hemmer to handle extreme variations in bulk, such as caused by heavy cross seams, it may be split longitudinally into two sections, one of which is mounted on a spring-pressed arm pivoted forwardly and at one side of the hemmer mouth.

In the accompanying drawings Fig. 1 is a plan view of the bed of a sewing machine showing the hemmer in operative position. Fig. 2 is a section on the line 2—2, Fig. 1. Fig. 3 is a rear end elevation of the hemmer. Fig. 4 is a left side elevation of the hemmer. Fig. 5 is a bottom plan view of the hemmer and Fig. 6 is a perspective view of a modified form of hemmer embodying the invention.

In the accompanying drawings 1 represents the throat-plate, 2 the feed-dog, 3 the presser-foot and 4 the needle of an ordinary sewing machine, to the cloth-plate 5 of which is secured the slotted shank 6 of the support 7 for the hemmer body. The support 7 is formed with a vertical, fold-guiding flange 8 to the face of which is secured at 9 the fixed scroll-section 10 of the hemmer body. The movable scroll-section 11 of the hemmer body, which is a continuation of the fixed scroll section 10, is carried by an arm 12 overhanging the fixed scroll-section 10 and constituting a lateral extension of the spring-pressed arm 13 pivoted at 14 forwardly and at one side of the mouth of the hemmer. The two sections of the hemmer scroll meet along the line 15 and are held yieldingly in contact with one another along such line by the spring 16, one end of which is fixed to the arm 13 adjacent the pivot screw 14 while the other end bears against the vertical flange 8.

The hemmer body is in the form of a scroll or counter-clockwise diminishing spiral as indicated by the longer arrow in Fig. 2. Such diminishing spiral terminates in a hollow or concavo-convex arbor 17 having an inner free edge 18 which is unattached to the adjacent or main wall portions of the scroll. The inner edge 18 is cut away at the delivery end 19 of the hemmer, Figs. 4 and 5, and does not obstruct the exit from the hemmer of bulky portions of a hem, such as caused by double folded portions of an irregular edge or by cross-seams. Preferably the inner free edge 18 of the scroll is in the form of a longitudinally and clockwise progressing spiral, as indicated by the shorter arrow 110

in Fig. 2; such spiral terminating at 18' at the delivery end 19 of the hemmer. The hollow arbor 17 is also of longitudinally and clockwise progressing spiral form and is of funnel shape with an open entrance. The body of the hemmer is extended at 20 to form a broad lip or platform for supporting the edge-portion of the work and facilitating its introduction into the hemmer scroll. This 10 lip does not extend to the delivery end of the hemmer but is cut away so as to terminate at the edge 20' which is curved at one end to merge into the main vertical wall of the scroll at its delivery end. Thus the hemmer 15 scroll has substantially no bottom wall at its delivery end, since such walls of both the outer and inner portions of the scroll have been cut away. The front edge 20^a of the platform 20 and the front edge 20^x of the hemmer body form a continuous spiral extending rearwardly as far as the point 17^a or base of the arbor where it merges into the front edge 17^b of the arbor and continues spirally in a reversed direction, or forwardly 20 to the front end of the arbor.

It will be seen that the inner or enclosed portion of the hemmer scroll is, in the present instance, in the form of a spiral concavo-convex arbor which extends forwardly from 30 the delivery end of the hemmer and in advance of the forward edge 20^x of the upper wall portion of the hemmer scroll. This arbor, together with the front edge portions 20^a and 20^x of the hemmer body and platform 35 operate to smoothly fold or roll in any irregularities or offsets in, or projections from, the edge of the fabric. The arbor, being in advance of the delivery end of the hemmer, does not obstruct the restricted space 40 at such end and interfere with the exit from the hemmer of thickened hem portions caused by such folded-in irregularities. In hemming material having heavy cross-seams, the movable section 11 of the hemmer will 45 swing about the screw 14 as a center toward the dotted line position, Fig. 1, sufficiently

to permit the cross seam to pass, whereupon such section will return to its initial position in contact with the fixed section 10.

For the usual run of work the two sections 50 of the hemmer shown in Figs. 1 to 5, inclusive, may be permanently jointed or made in one piece, as shown in Fig. 6, it being unnecessary to split the scroll into fixed and movable sections except to handle work having heavy cross-seams or extreme variations in thickness.

Having thus set forth the nature of the invention, what I claim herein is:—

1. A hemmer comprising a hem-folding scroll formed as a diminishing spiral terminating in a hollow arbor having an inner free edge extending spirally toward the delivery end of the hemmer, said scroll including a work-supporting platform disposed mainly in advance of said arbor, said platform and the body of the hem-folding scroll having a front edge extending spirally rearwardly toward the delivery end of the hemmer and merging into the front edge of said arbor, which latter front edge continues spirally forwardly to the front end of said arbor.

2. The construction set forth in claim 1 wherein the bottom wall of said arbor and the rear end portion of said platform are cut away approaching the delivery end of said hemmer.

3. A hemmer having a support formed with a fold-guiding flange, a hem-folding scroll divided longitudinally into two sections one which is fixed to said support at one side of said flange, a spring-pressed arm extending in the direction of feed and pivotally mounted at its front end on said support at the other side of said flange and having a lateral extension overhanging said flange, the other of said sections being carried by said lateral extension.

In testimony whereof, I have signed my name to this specification.

ALBERT HARRISON DE VOE.
